(57) **CLAIM**

An ornamental design for the firearm charging handle, as shown and described.

DESCRIPTION

FIG. 1 is a top view of my firearm charging handle; and, FIG. 2 is an elevated front perspective view of the firearm charging handle shown in FIG. 1, comprising a top surface of the firearm charging handle.

The broken lines are included for the purpose of illustrating the environment and form no part of the claimed design.

1 Claim, 2 Drawing Sheets
